PLUMBING FIXTURE AND ACCESSORY
THEREFOREarl Dellon, New York, N. Y., assignor to Paragon
Utilities Corp., New York, N. Y., a corporation
of New York

Application July 19, 1944, Serial No. 545,696

2 Claims. (Cl. 4—189)

1

This invention relates in general to kitchen sinks, washtubs, lavatories, laboratory sinks and like, and more particularly, to plumbing fixtures which employ two or more sinks or tubs, as for example, a kitchen fixture having two sinks or a sink and washtub combination; a washroom array of multiple lavatories; or an array of closely spaced laboratory sinks, etc. The invention, more specifically, relates to means for spacing, separating and supporting two or more sinks or tubs forming a single fixture, and also to the drain board or cover top for the individual sinks or tubs of the fixture.

An object of this invention is to provide a simple means, which may be inexpensively made in a single piece, for separating and aligning two sinks or tubs at the required spacing in the said single fixture or array. Allied with this object, a further purpose is to implement the said spacing means with means attached to the spacer for supporting or hanging the individual sinks or tubs. The said spacer is designed so that water or other material will be drained off the spacer and be directed to the sink or tub on either side thereof. An important object of this invention is to provide a spacer of the character described which will present a neat and pleasing appearance to the top exposed view of the two (or more) sinks or tubs, at the juncture of the individual spaced sinks or tubs. A still further object is to provide a spacer of the character described which will make possible the use of a sliding top cover which will cover, in a duplex fixture, one of the two sinks or sink-tub combination and will expose the other one.

For the attainment of the foregoing and such other objects as may be pointed out or appear herein, I have shown an embodiment of my invention in the accompanying drawing, wherein—

Fig. 1 is a perspective view of a kitchen sink cabinet having duplex sinks or a sink-tub combination embodying my invention;

Fig. 2 is a top plan view of a duplex kitchen sink of this invention;

Fig. 3 is a sectional view taken on the line 3—3 of Fig. 2, through one of the sinks and the improved slide cover of this invention;

Fig. 4 is a section on line 4—4 of Fig. 2, through a portion of the improved spacer and supporting bar at the juncture of the two sinks;

Fig. 5 is a partial section on line 5—5 of Fig. 2, showing the juncture between the two tubs and also a cross-section through the improved spacer and supporting bar;

2

Fig. 6 is a top view of the spacer, somewhat enlarged;

Fig. 7 is a bottom view, somewhat enlarged, of the juncture between the two sinks, showing the supporting bar; and

Fig. 8 is a perspective view of the supporting bar.

Merely for facility in description and illustration, this invention will be described in conjunction with the duplex kitchen sink cabinet shown in Fig. 1 and designated 1, although it is to be understood that the invention may be applied, as pointed out above, to any plumbing fixture or array having two or more sinks or tubs. The illustrated fixture 1 has a left and a right sink, respectively, 2 and 3, which for convenience are shown as identical in all respects. The fixture or cabinet has a top 4, surrounding the two sets in sinks, which may be made of plywood or the like faced with inlaid linoleum and may be bound with stainless steel or Monel metal trim 5 which may also be provided around the back splasher board 6. In particular, the stainless steel or Monel metal trim will, in the preferred embodiment of my invention, surround the sink opening in top 4, this trim border being designated 7. As best shown in Fig. 2, the trim border 7 surrounding the sink opening is curved at the four corners to parallel the curvature of the interior 30 of the sinks.

The provision of a single large opening in the cabinet top for exposing both sinks is an innovation in the construction of kitchen cabinets; in all prior models of which I am aware the top is provided with two openings, one for each sink, the juncture or space between the two sinks being concealed by a narrow strip portion of top separating the two sink openings. One reason for the provision in the improved fixture of this invention is that of appearance. A second reason is that by so providing a single large opening, I may use a sliding cover, designated 8 of size to cover one sink unit (the left sink in Figs. 1 and 2) and to expose the other sink unit. The 40 four corners of slide cover 8, which may be made, like the cabinet top, of plywood faced with inlaid linoleum, is curved to the same curvature as the aforementioned curved corners of the sink opening and the metal surrounding trim 7, so that the 45 slide cover will fit neatly in either of its left or right positions. Slide cover 8 is supported or suspended from the parallel lengths of the metal trim 7 at the front and rear sides of the opening by means of L-shaped stainless steel or Monel 50 metal lengths 9 secured as by nailing, to the front 55 metal lengths 9 secured as by nailing, to the front

and rear side edges of the cover slide, see also Fig. 3.

The juncture or space between the juxtaposed sides of the sinks appearing or exposed in the larger sink opening in the cabinet top presents an unsightly and unsanitary appearance. Any means employed to cover or conceal this unsightly space between the two sinks must permit the operation of slide cover 8. I have solved both problems (and others to be mentioned) by providing a single-piece member 10 which I have termed a "spacer," shown in detail in Fig. 6, and which may be made of metal, either cast, stamped, or welded sections of ceramic, wood, plastic, and the like, although I prefer to use a metal to match the aforementioned trim 7. Spacer 10, at least as to the portion thereof which is disposed between the front and rear edge of the sink opening, is sectionally in the form of an exaggerated T having a wide horizontal web 11, Fig. 5, resting on the rolled edges 2e and 3e of the spaced sinks 2 and 3, respectively, and a short vertical rib 12 received in the space between the two sinks.

As best shown in Fig. 4, the thickness of horizontal web 11 at its highest point is such that sufficient clearance is provided above it for passage of slide cover 8. And, as best shown in Fig. 5, the horizontal web 11 is crowned with a center high point and sloped towards both sides so that water or other matter will drain to either side into sink 2 or 3 depending upon the position of the slide cover. The dimension of the short vertical rib 12 is such, see Fig. 5, that it fits snugly between the two sinks to separate and align them at the proper spacing. The ends of the main portion of the spacer, i. e., the part 11 which is exposed to view and disposed in the sink opening of the cabinet top, are provided with parallel shoulders 13, see Fig. 6; the distance between parallel edges 13 of the spacer is such that the spacer fits snugly between the front and rear sides of the sink opening, with the shoulders 13 fitting against the said sides, see Figs. 6 and 4.

The ends of the spacer, beyond the shoulders 13, are stepped down and terminate in triangular ends 14, Fig. 6, which fit against the underside of the cabinet top 4, see esp. Fig. 4. As clearly shown in Fig. 6, the exposed portion 11 of the spacer near its end shoulders 13 is curved to the same or substantially the same curvature as that of the sinks or tub, see Fig. 2. The triangular ends 14, on the other hand, are merely cut away or recessed by the straight sides of the triangle—in order to clear the outside corner edges of the sinks, see Fig. 2—since the triangular ends are not exposed and production costs may be reduced by using straight sides instead of curved ones. The triangular ends are provided with a pair of small holes 15 and a larger center hole 16. The spacer is secured by its said triangular ends 14 to the underside of the cabinet top 4 by wood screws passing through the smaller holes 15, see Fig. 7.

The sink or tub itself is supported from the underside of cabinet top 4 by a plurality of Z-shaped cleats 17; see Fig. 3; which are secured by wood screws to the underside of top 4 and which are spaced around three sides of the sink, i. e., all sides except the facing or juxtaposed

sides of the pair (or pairs, where an array of more than two sinks are used) of sinks. The juxtaposed sides of the sinks are held up by a common supporting bar 18, shown in perspective in Fig. 8, and provided with end holes 26 which align with the center holes 16 of spacer 10, see Figs. 7 and 4. The rolled edges of the two juxtaposed sinks rest on the common supporting bar 18, as best shown in the bottom view of Fig. 7. A common wood screw passes through both aligned holes 26 of the supporting bar 18 and 16 of the spacer 10 and screws into the underside of the cabinet top, see Fig. 4.

I claim:

1. An accessory for a multiple-sink fixture having a top provided with an opening for a plurality of rolled-edged sinks, said accessory comprising a spacer having a main portion of exaggerated T cross section presenting a horizontal web and a vertical rib, the said vertical rib being received between two juxtaposed sinks and the said horizontal web overlying the rolled edges thereof and the space therebetween, the ends of the spacer terminating in stepped-down ends adapted to underlie the said fixture top and provided with holes to receive wood screws to secure the spacer to the said top, the said stepped-down ends of the spacer being apertured, and a supporting bar having apertured ends alignable with the said end apertures of the spacer and secured to the underside of the fixture top by wood screws passing through the said aligned apertures, the said bar being adapted to underlie the rolled edges of the juxtaposed sides of the sinks to support the same.

2. A spacer for a multiple-sink fixture having a top provided with an opening for the said plurality of sinks; said spacer having a main portion of exaggerated T cross section presenting a horizontal web and a vertical rib, the said vertical rib being received between the two juxtaposed sinks and the said horizontal web overlying the edges thereof and the space therebetween, the ends of the spacer terminating in stepped-down ends adapted to underlie the said fixture top and provided with holes to receive wood screws to secure the spacer to the said top.

EARL DELLOON.
